UNITED STATES PATENT OFFICE.

EDWIN J. YOUNGS, OF FLINT, MICHIGAN, ASSIGNOR TO THE CASTREE MALLERY COMPANY, OF SAME PLACE.

SLEIGH-KNEE.

SPECIFICATION forming part of Letters Patent No. 399,642, dated March 12, 1889.

Application filed October 16, 1888. Serial No. 288,203. (No model.)

To all whom it may concern:

Be it known that I, EDWIN J. YOUNGS, a citizen of the United States, residing at Flint, in the county of Genesee and State of Michigan, have invented a new and useful Improvement 5 in Sleigh-Knees, of which the following is a specification.

The object of this invention is to provide a simple, cheap, durable, and effective sleigh-knee, wherein all loose joints and connections are avoided; and it consists in a certain novel construction and combination of devices fully described hereinafter in connection with the accompanying drawings, and specifically 15 pointed out in the appended claims.

In the drawings, Figure 1 is a perspective view of a bob-sleigh provided with my improvements. Fig. 2 is a side view partly in section. Fig. 3 is a transverse sectional view 20 taken centrally through one of the knees.

Referring by letter to the drawings, A A designate the runners, to which are attached the standards B B, having transverse channels b b in their upper ends; and C designates 25 a flat metallic torsion-plate, which is arranged at its ends in the said channels and is bolted securely to the standards.

D designates pins which are rigid with the standard, (preferably formed integral there- 30 with, as shown in the drawings, Figs. 2 and 3,) and they extend vertically through apertures c near the ends of the torsion-plate and extend a short distance above the same.

E designates the beam, which is provided 35 at its ends with downwardly-tapered openings or slots e e, which align with apertures f in the convex plates F, which are affixed to the lower side of the beam at its ends. The rounded under sides of these convex plates 40 bear on the upper side of the torsion-plate, and the pins D pass through the registering-openings in the beams and the plates and thereby hold the same in place on the knee.

The beam is provided on its upper side with 45 transverse grooves G, having rounded floors, and H H represent metallic braces which are secured at their ends to the runner in front and rear of the knees and pass at intermediate points through the said grooves in the 50 beam. These braces are provided with cen-

tral apertures, h, which fit over the upper ends of the pins D. The king-bolt I extends vertically through registering-openings in the centers of the torsion-plate and the beam, and the bolster K is mounted on the upper ex- 55 tended end of the said king-bolt and bears on the upper side of the beam. The front end of the reach L is attached to a plate, l, which is secured to the bolster by means of the said king-bolt.

The advantages of this sleigh will now be readily seen. As the runners pass over an uneven surface, they rock or oscillate freely, thereby twisting the torsion-plate "he said plate by its spring action bringing the 60 runners back to their proper position after the strain is removed. Thus the opposite knees are connected firmly together, so that lateral strain is resisted and at the same time free oscillating movement is allowed. When 65 the runners are oscillated, the beam remains stationary, owing to its connection with the bolster, and the torsion-plate rocks on the lower side of the beam. It will be readily understood that the peculiar manner of connecting the beam to the standard is calculated to allow free oscillatory movement of 70 the latter.

I am aware that it is old to provide connections between the beam and the knees 75 whereby a free oscillating movement of the latter is permitted, and this I do not desire to claim. The looseness of the runners, due to the usual manner of connecting them, is, however, objectionable, and to overcome this 80 objection I connect the opposite knees by a transverse plate or bar of any desired sectional shape, (preferably flat,) which twists when the runners are strained and returns the latter to their original relative positions 85 when the strain is removed.

Having thus described the invention, I claim—

1. In a bob-sleigh, the combination, with the standards secured to the runners at opposite points, of the torsion-plate connected at its ends to the standards, and the bolster swiveled at its center to the torsion-plate, whereby the runners are allowed free oscillating movement independent of each other 90 95 100

- and of the bolster, substantially as and for the purpose specified.
2. In a bob-sleigh, the combination, with the standards attached to the runners, of the torsion-plate connecting the upper ends of the said standards, and the beam provided on its under side with convex plates bearing on the torsion-plate and secured in position by vertical pins, substantially as specified.
- 10 3. In a bob-sleigh, the combination, with the standards affixed to the runners and provided at their upper ends with vertical pins D, of the torsion-plate connecting the upper ends of the standards and provided with apertures fitting over the said pins, the beam provided with tapered openings or slots fitting the pins, and the convex plates on the under side of the beam bearing on the torsion-plate, substantially as specified.
- 20 4. In a bob-sleigh, the combination of the runners, the standards secured to the runners and provided with the transverse channels b in their upper ends, the torsion-plate affixed at its ends in the said channels, the pins D rigid with the standards and passing vertically through the said torsion-plate, the beam provided with openings fitting over the pins and having convex plates bearing on the torsion-plate, and the braces secured at their
- ends to the runners and passing at intermediate points through transverse grooves in the upper side of the beam, substantially as specified.
5. In a bob-sleigh, the runners having the standards, the pins D, extending upward from and rigid with the standards, the torsion-plate F, extending across and connecting the standards, the beam E, rounded on the under side and bearing at said rounded side on the torsion-plate, the tapered openings in the beam, through which openings the pins D pass, and the braces H, connected with the runners and passing over the top of the beam and receiving the upper end of the pins D, as set forth.
- 40 6. In a bob-sleigh, the runners having the standards, the torsion-plate T, extending across and connecting the standards, and the beam E, rounded on the under side and bearing at said rounded side on the torsion-plate, as set forth.
- 45 In testimony that I claim the foregoing as my own I have hereto affixed my signature in presence of two witnesses.
- EDWIN J. YOUNGS.
